GAS VALVES FOR USE IN FLUE BETWEEN A GAS PRODUCER AND A CONSUMING UNIT FOR THE GAS, e. g., A FURNACE

Eric A. Greenway, Huyton, and James J. Whiteheart, Liverpool, England, assignors to Pilkington Brothers Limited, Liverpool, England, a British company

Application July 14, 1955, Serial No. 522,133

Claims priority, application Great Britain July 21, 1954

5 Claims. (Cl. 137—251)

This invention relates to gas valves for use in the flue 15 between a gas producer and a consuming unit for the gas e. g. a furnace.

Valves of this description are usually located in the flue at the point where the latter turns at right angles from the vertical to the horizontal and are made of cast iron in circular form. They have a bevelled seating edge, which seals against a corresponding bevelled seating in a cast iron plate, in similar fashion to a poppet valve in an internal combustion engine. Sealing of the valve is effected by accurate metal-to-metal contact, but the relatively high temperature of producer gas in the flue tends to cause more or less warping of the valve parts, and in consequence a leakage of gas would take place between the valve and its seating if it were not for the fact that the valve becomes sealed by tar deposited by the gas.

This condition, however, is very inconvenient when it becomes necessary to operate the valve, because the tar may cause it to adhere to its seating so firmly that great force is needed to lift it, and it is also very difficult to make the valve seat properly when it is again closed. Moreover, such a valve often begins to leak in spite of the deposited tar, and when this happens the work of sealing the valve has to be done in an atmosphere of gas, which is dangerous and may give rise to accidents.

It is the main object of the present invention to provide a gas valve of improved design in which the disadvantages aforesaid are avoided.

A further object of the invention is to provide a gas valve which is simple to produce and at the same time is particularly effective in operation, and remains in good working condition unaffected by tar and other matter deposited by the gas.

According to the invention, a gas valve for location in a flue between the gas producer and a consuming unit for the gas e. g. a furnace where the gas flow is made to vary its direction from vertical to horizontal comprises a liftable and lowerable hood open on the underside towards the vertical passage of the flue, the wall of said hood towards a horizontal passage or passages of the flue being cut away to form an aperture providing communication between the interior of the valve and the said horizontal passage or passages in the lifted position of the hood, and a deep narrow open trough in association with the vertical flue passage to form a liquid seal for the hood wall in the lowered position thereof.

Preferably the hood is of polygonal e. g. rectangular form in plan view, one or more walls being cut away in a form providing predetermined characteristics in respect of the cross-sectional area of each aperture in relation to the extent of movement of the hood, the cut away portions providing communication with corresponding horizontal flues and the vertical flue.

Means may be provided for effecting a continuous supply of sealing liquid to the said trough, together with an overflow pipe for discharging surplus liquid from the trough. The overflow pipe itself may be provided with its own liquid sealing trough externally of the valve.

2

The valve may be operated by a valve stem extending through the wall of the flue and connected to the top of the hood, a deep narrow open trough adapted to form a liquid seal being secured to the top of the flue surrounding the said stem and a concentric skirt secured to an upper part of the said stem being arranged to dip into the said trough. The trough surrounding the stem may be furnished with means for effecting a continuous supply and discharge of the sealing liquid to and from the trough.

The concentric skirt secured to the valve stem may be graduated in accordance with the characteristics of the opening cut away in the wall of the hood so that it indicates the extent of opening the valve. This indication in conjunction with indications of the gas pressures in the inlet and outlet passages to each side of the valve, which pressures may be indicated by suitable manometers connected to those passages, provides a measure of the rate of flow of gas through the valve, which then serves as a variable-orifice metering device.

In order that the invention may be more clearly understood, a preferred embodiment thereof will now be described, by way of example, with reference to the accompanying diagrammatic drawing, which shows in perspective view, partly broken away, a gas valve according to the invention controlling gas to one horizontal outlet flue.

The drawing illustrates the conduit between a gas producer and a furnace at the point where it turns at right angles from vertical to horizontal, the vertical passage being indicated at 1 and the horizontal passage at 2. The conduit, which may consist of steel, is preferably lined with a heat-insulating machine such as refractory brick as at 3, and in addition the steel casing may also be set in brickwork (not shown).

The valve itself comprises a hood 4 including a top portion 5 and four depending peripheral wall parts, the said hood being open at the bottom towards the vertical passage of the flue. The side wall part 6 of the hood facing the horizontal passage 2 is cut away except for a portion left deep enough to serve as a sealing lip.

About the vertical passage 1 of the flue there is provided a trough 7 connected to the outer wall of the flue along the bottom, the inner face of the trough being formed by the outer wall of the flue. This rectangular trough is adapted to receive water and to act as a water seal, so that when the hood is lowered so that all four walls are immersed in the water contained in the trough 7 a completely gastight closure is obtained.

The valve is opened by lifting it by means of a stem 8, which is pinned to angle-iron stiffeners 9 welded to the top 5 of the hood, the sealing lip formed by the wall part 6 thereby being lifted out of the water in the sealing trough 7.

To preserve balance in the hood a mass (not shown) may be attached either on the inside of the wall part 6 or of the top portion 5, equal in weight to the amount of metal missing from that side of the hood in making the wall part 6 of less depth than the three other wall parts of the hood.

When the valve is open, gas has access to the space between the top 5 of the hood and the upper wall of the flue, so that a seal must be provided around the stem 8 where it passes through the top of the flue. This takes the form of a deep water-sealing trough comprising two concentric tubes 10 and 11, preferably of steel, welded to a base flange 12 secured to the top of the flue, and a concentric skirt 13 secured to the stem at 14 and dipping into the trough 10, 11, the said skirt having a diameter about midway between the diameters of the two tubes forming the trough 10, 11.

To replace water lost by evaporation and to carry away

any deposits of tar or soot on the exposed water surfaces a continuous supply of water is provided to the trough 7 at 15 and the trough 10, 11 at 16. The water enters at the bottom of each trough, and passes out at the top of each trough through overflow pipes, such as the pipe 17 leading from the trough 7 and the pipe 18 leading from the trough 10, 11. In this way a constant level of water is maintained in each trough.

The continuous flow of water through the sealing troughs as described is of considerable advantage in preventing overheating of the working parts, i. e., the hood, valve stem and so forth, and contributes greatly towards keeping the valve in good condition.

In case an accumulation of silt in the bottom of trough 7 occurs, doors (not shown) may be provided at the bottom of the trough e. g. at opposite corners to allow takes to be inserted to remove the silt as will be readily understood, a similar door may be fitted to the trough 19.

As the overflow from the trough 7 comes from a space which contains gas when the valve is open, the overflow pipe 17 is provided with its own water seal in the form of a small tank 19, into which the pipe 17 dips. The depth to which the pipe 17 dips below water level in the tank 19 must be at least as great as the maximum water gauge height of the pressure of the gas in the horizontal flue 2. The small tank 19 is provided with an overflow pipe 20.

It would of course be possible to provide an external seal to the overflow 17 by making the pipe 17 in the form of a U-tube. However, this tube might become blocked by tar, soot and the like deposited from the gas. In the small open tank 19 these deposits come to the surface of the water and are carried away by the overflow.

The valve may be used so that gas passes through it in either direction. Usually the arrangement is such that gas flows up through a vertical passage and out of the valve into a horizontal passage of the flue. The cross-sectional dimensions of the flue may vary according to requirements and may range, for example, between one foot square and six foot square. However, the invention is in no way limited to a particular size.

The cut-away wall part 6 of the hood may be of any predetermined form for giving desired characteristics to the cross-sectional area of the valve aperture in relation to the extent of movement of the hood. For example, if it were desired that the valve opening should be linearly proportional to the distance through which the hood is lifted, a plain rectangular aperture can be provided as shown. If on the other hand the aperture were required to change more rapidly than in linear proportion to the vertical movement of the hood, the aperture could take the form of, say, an inverted V. If a small definite opening were required just short of total closure, this could be provided by furnishing a notch of appropriate width and depth in the top edge of a rectangular aperture or, in the case of an inverted V opening, by the provision of a top parallel portion of suitable relatively narrow width instead of a sharp apex.

By graduating the tube 13 attached to the valve stem 8 in accordance with the shape of the opening in the wall 6 of the valve hood 4 the valve may be used, in conjunction with pressure indicating devices, such as manometers connected to the inlet and outlet flues, as a variable orifice for metering the gas passing through it.

The normal working pressure of producer gas is about 2" water gauge. It may, however, rise to about 12" water gauge or more, and the minimum depth of each seal should therefore be at least equal to this maximum water gauge height.

The hood construction may be duplicated by a vertical dividing wall where two contiguous vertical flues are concerned, a water seal trough being disposed between the flues to accommodate the dividing wall. Thus, outer hood walls e. g. opposite walls may be cut away to control flow from either vertical flue to a horizontal passage

or to independent passages, and the flues may be made to communicate through the said dividing wall, if the latter is of lesser height than the wall parts 6 of such structure. Alternatively two hoods may be arranged back to back in a vertical flue to be independently movable, in which case the trough 7 is provided with a medial trough, making the water seal for the hoods walls of Figure 8 form, instead of purely rectangular form hereinbefore described.

In the foregoing description reference has generally been made to gas flow from the vertical flue to a furnace but clearly the hood construction can be used to regulate a reverse flow through the hood into the flue or flues, as the case may be, so that where a duplicate hood structure is employed the reverse flow through the hood may be into either or both of the vertical flues.

By the provision of the refractory linings to the troughs in the flues there is substantially no loss of heat from the flue gases through the valve.

By the present invention a seal is obtained which maintains a perfect seal against the flow of gases through the flue, in contradistinction to valve constructions hitherto employed in which the seating of the valve may be impaired by deposits from the flue gases or as a result of distortion of the valve or its seating due to the temperature of the gases passed by the valve.

Experiments have demonstrated that the valve structure hereinbefore described and illustrated may be successfully used as a metering device to determine the rate of flow of gas through it; and that it is especially superior to the ordinary form of valve in providing immediate positive closure when it is necessary to switch flue connections, as, for instance, when changing from one gas-producer to another for the supply to a glass melting furnace or furnaces. There is no mechanical resistance to closure, and the graduated stem shows when the valve is in the closed position, so that one knows for certain that there is then a perfect seal thus obviating the usual practice when using ordinary valves of going into the valve chamber to inspect the working of the valve, and where necessary to tamp clay in to stop leaks.

We claim:

1. A gas valve and seal therefor to control flow of gas between two passageways, one of which is substantially vertical, the other being substantially horizontal, comprising a valve body in the form of a hood adapted to be supported for vertical movement in the vertical passageway and across the end of the horizontal passageway into open position in which the flow of the gas between the two passageways is permitted and into closed position in which the flow of the gas between the two passageways is blocked, said valve body having a top wall in exposed position to be in the path of gas flow between said passageways in installed position of the gas valve, and a peripheral wall depending from said top wall and forming a unit with said top wall movable in unison therewith into open and closed positions, the part of said peripheral wall which is nearest the horizontal passageway in installed position of the gas valve, being shorter than other parts of said peripheral wall to form an opening in said peripheral wall between said other longer parts flanking said shorter part for the flow of gas between said passageways in open position of said valve, said shorter wall part being sufficiently long to block passage of gas between said passageways in closed position of the valve, and a seal comprising a trough having the configuration of the hood and adapted to contain liquid for a liquid seal, said trough being in position to receive in the liquid therein the entire lower section of the wall including that of the shorter part to seal said valve in closed position of the valve and being in position to receive in the liquid therein the lower section of the longer wall parts in open position of said valve, in the operation of the gas valve and seal, all the longer parts of the peripheral wall being immersed within the liquid in the trough throughout the complete range

of movement of the hood from a fully closed to a maximum open position of the valve.

2. An apparatus for conducting gas and for controlling its flow, comprising a conduit for the flow of gases comprising a substantially vertical passageway and a substantially horizontal passageway, and a valve and seal therefor for controlling flow between said passageways, comprising a valve body in the form of a hood supported for vertical movement in the vertical passageway and across the end of the horizontal passageway into open position in which the flow of the gas between the two passageways is permitted and into closed position in which the flow of the gas between the two passageways is blocked, said valve body having a top wall in exposed position to be in the path of gas flow between said passageways in open position of said valve, and a peripheral wall depending from said top wall and forming a unit with said top wall movable in unison therewith into open and closed positions, the part of said peripheral wall which is nearest the horizontal passageway being shorter than other parts of said peripheral wall to form an opening in said peripheral wall between said other longer parts flanking said shorter part for the flow of gas between said passageways in open position of said valve, said shorter wall part being sufficiently long to block passage of gas between said passageways in closed position of the valve, and a seal comprising a trough around the passage defined by said vertical passageway having the configuration of the hood and adapted to contain liquid for a liquid seal, said trough being in position to receive the entire lower section of the wall including that of the shorter part to seal said valve in closed position of the valve and being in position to receive in the liquid therein the lower section of the longer wall parts in open position of said valve, in the operation of the valve, all the longer parts of the peripheral wall being immersed within the liquid in the trough throughout the complete range of movement of the hood from a fully closed to a maximum open position of the valve.

3. The combination according to claim 1, comprising a valve stem connected to said top wall for operating said valve into open and closed position and means for holding sealing liquid in contact with said stem and for forming with the sealing liquid a seal to prevent leakage of gas from the vertical passageway along said stem.

45

4. The combination according to claim 2, comprising a valve stem connected to said top wall and passing through a top wall in said vertical passageway for operating said valve into open and closed positions, and a seal for said stem to prevent leakage of gas from the vertical passageway along said stem, and comprising a trough secured to the top wall of the vertical passageway and surrounding said stem, a concentric skirt secured to an upper part of said stem and dipping into said trough, and means for effecting a constant supply and discharge of the sealing liquid to and from the last mentioned trough.
5. A hollow gas valve and seal therefor, the valve comprising a body in the form of a hood open at the bottom and including a peripheral wall, one part of said wall being shorter than the other parts of said wall, the seal comprising a trough below the top wall of said hood in registry with said wall and having the general configuration of the hood, said trough being adapted to hold liquid and to receive said peripheral wall to form a liquid seal therefor when the hood is lowered in valve closed position to block flow of gas through the hood and out from under said wall, the trough being of a depth and the longer parts of the wall being of a length to maintain the longer parts of the wall in said trough sealed by the liquid therein when the hood is raised into maximum valve opened position with the lower edge of the shorter wall part raised above the liquid in the trough into position to form a valve outlet between the shorter wall part and the trough, whereby the gas is permitted to flow through the hood and out through said outlet in valve opened position.
